United States Patent Office

Des. 195,387
Patented June 4, 1963

195,387

HOLDER FOR COLLETS

Harry F. Cygan, Berwyn, Ill., assignor of fifty percent to George W. Valsa, Brookfield, Ill.

Filed Apr. 17, 1961, Ser. No. 64,776

Term of patent 14 years

(Cl. D80—9)

I claim:

The ornamental design for a holder for collets, as shown and described.
